UNITED STATES PATENT OFFICE.

MACK D. JEFFRIES, OF BRONX, NEW YORK.

RETAINING DEVICE FOR PURSES.

Application filed September 2, 1925. Serial No. 54,050.

This invention relates to improvements in theft preventing devices, particularly devices for preventing the stealthy extraction of pocket-books or the like from a pocket and it is the principal object of the invention to provide a pocket-book or the like with a theft preventing device which does not in the least disturb or hinder the normal use of the pocket-book or distract from its customary appearance.

Another object of the invention is the provision of a pocket-book equipped with a theft preventing device positively preventing a stealthy removal of the pocket-book.

A further object of the invention is the provision of a device positively preventing the theft of pocket-books from the pockets of the owner, and which is of simple and inexpensive construction, and can be readily attached to any of the pocket-books now in the market.

A still further object of the invention is the provision of a theft preventing device for the pocket-book which can be readily operated in order to project two bars adapted to retain the pocket-book securely in the pocket, and which are equipped with a means for preventing tearing of the material of the pocket.

These and other objects and advantages of the invention will become more fully known as the description thereof proceeds, and will then be more specifically defined in the appended claims.

In the accompanying drawing forming a material part of this disclosure:

Fig. 1 is a rear view of a pocket-book equipped with a theft preventing device constructed according to my invention.

Fig. 2 is a front elevation of the theft preventing device for pocket-books according to the present invention in its inoperative position, on an enlarged scale.

Fig. 3 is a view similar to Figure 2, showing the device in the operative position.

Fig. 4 is a sectional end view thereof.

Fig. 5 is a sectional central view.

Fig. 6 is a perspective view of the operating bars and their springs.

Fig. 7 is a top edge view.

The device comprises a rear or base plate 10 having marginal turned over flanges 11 for the holding and securing of the cover plates 12 and 13.

The rear wall or plate 10, forming a casting or frame is composed of two parts

hingedly attached to a central pintle 14 having suitable perforations intermediate its ends allowing the passage of two juxtaposed sliding bars 15 and 16 adapted to extend with their outer ends through eyelets 17 and 18 in the side walls of a pocket-book 19 to which the device is secured by stitches underneath the lining of the pocket-book. The outer ends of the bars 15 and 16 are formed into heads 20 and 21 which are equipped with rubber or the like tips, for preventing the tearing or damaging of the material of a pocket. The bars 15 and 16 are equipped intermediate their ends with notches or recesses 22, 23 adapted to be brought into alignment when the bars are pushed inwardly, and adapted to be engaged by a finger 24 at the lower end of a lever 25 pivoted intermediate its ends, as at 26, to the rear wall 10 and having its opposite end formed into a handle 27. A spring 28 is attached at one end to the end wall of the plate 10, while its other end is hooked into a perforation of lever 25, as at 29. The inner ends of the bars 15 and 16 are formed into brackets 31, 30 having perforated depending arms into which are hooked the ends of springs 32, 33, as at 34, 35, the outer ends of these springs are attached to the frame or plate 10, as at 36, 37, respectively.

The operation of the device will be entirely clear from the above description. If the pocket-book is to be used in the customary manner, the finger 24 will engage the aligned recesses 22, 23 of bars 15 and 16, and keep the bars locked in their inner positions against the action of the springs 32, 33 as shown in Figure 2. If the pocket-book is placed into a pocket, the handle 27 is operated to disengage finger 24 from the recesses 22, 23 of bars 15 and 16, and these bars will be projected outwardly by the action of the springs 32 and 33 as shown in Figure 3, to engage the material of the pocket.

It will be clear that it will be impossible to extract the pocket-book from the pocket without arousing the attention and suspicion of the wearer.

While I have shown and described the preferred form of my invention as an example, it will be clear that many changes such as come within the scope of the appended claims may be made without departure from the spirit of the invention.

Having thus described my invention, what I claim as new and desire to secure by Letters Patent is:

1. A theft preventing device for pocket-books comprising a casing, a pair of juxtaposed recessed sliding bars within said casing adapted to be projected laterally therefrom, a pivoted lever having a finger adapted to engage the recesses of said bars when in alignment, a spring for controlling said finger, a handle for operating said lever, a depending bracket arm at the inner ends of said bars, springs secured on said arms and to the end bars of said frame, said springs adapted to project said bars out of the frame upon the release of said finger from the recesses of said bars, by the operation of said handle and rubber mounted heads on the outer ends of said bars adapted to engage the material of the pocket upon the projection of said bars.
2. A theft preventing device, or the like,

for pocket-books, or the like, comprising a casing, supporting a pair of juxtaposed laterally slideable bars, provided with recesses 25 aligned when said bars are in their innermost positions, and normally engaged by the finger of a lever pivotally mounted in said case, said lever being normally held with its finger thus engaged by the action of a spring having one of its ends fastened to said lever, and the other to said casing, the said lever having its free end projecting from the casing, forming a handle to disengage said finger from said recesses, and 30 springs having one of their ends fastened to said slideable bars, and the other of their ends to the casing, to project said slideable bars to an outward position upon the disengagement of said finger from said recesses.

In testimony whereof I have affixed my signature.

MACK D. JEFFRIES.
